RAILWAY TRAFFIC CONTROLLING APPARATUS

Henry S. Young, Wilkinsburg, Pa., assignor to
The Union Switch & Signal Company, Swiss-
vale, Pa., a corporation of Pennsylvania

Application April 13, 1938, Serial No. 201,740

7 Claims. (Cl. 246—219)

My invention relates to railway traffic controlling apparatus, and particularly to apparatus of the type involving a railway switch and a signal for governing traffic movements over the switch.

One feature of my invention is the provision of means responsive to a train approaching the signal for controlling the signal to display a first and a second indication alternately, and the provision of means for directing a train movement over the switch in its normal position or its reverse position according as the train passes the signal while the signal is displaying the first or the second indication, respectively.

The apparatus of my invention is an improvement over that disclosed in the copending applications Serial No. 323,286, filed December 3, 1928, by Lester E. Spray for Multiple control apparatus; and Serial No. 118,609, filed December 31, 1936, by John M. Pelikan for Railway traffic controlling apparatus.

I shall describe two forms of apparatus embodying my invention, and shall then point out the novel features thereof in claims.

In the accompanying drawing, Fig. 1 is a diagrammatic view showing a stretch of railway track including a switch, and a signal for governing traffic movements over the switch; and Fig. 2 is a diagrammatic view showing a stretch of railway track including a switch, and a signal for governing traffic movements toward a second signal which governs traffic movements over the switch.

Similar reference characters refer to similar parts in each of the views.

Referring first to Fig. 1, a stretch of railway track is shown including a switch 3. Switch 3 is operated by a mechanism designated by the reference character 3F, which is in turn controlled by means here shown as electro-magnets 3N and 3R.

The upper rail of the track, as shown in the drawing, is divided by insulated joints 4 to form sections 1T and A1T. Section 1T is provided with a track circuit including a relay 1TR connected across the rails adjacent one end of the section, and section A1T is provided with a track circuit including a relay A1TR connected across the rails adjacent one end of the section. Each of these track circuits, as here shown, includes also the secondary winding 6 of a transformer a connected across the rails adjacent the opposite end of the section. Primary winding 5 of each of the transformers a is energized by current from a suitable source not shown in the

drawing but having terminals designated by the reference characters BX and CX. Resistors 7 and 8 are included in track leads from transformers a and the track relays, respectively, in accordance with usual practice with the type of apparatus shown.

A signal 1 is shown adjacent the mutually abutting ends of sections 1T and A1T, so that section A1T is in the rear of signal 1 and section 1T is in advance of signal 1. As here shown, this signal is of the color light type comprising a green lamp G, a yellow lamp Y, and a red lamp R. Signal 1 may, however, be of any other suitable type.

A timing device or mechanism M, having a rotor 11 which turns about its axis in the direction indicated by the arrow, is set into operation when a car or train moving toward the right as shown in the drawing, which I shall assume is the eastbound direction, enters section A1T. Rotor 11, when device M is in operation, rotates contact segments 13 and 22 also in the direction indicated by the arrow. As shown in the drawing, segment 13 is in engagement with a contact finger 14. When device M is set into operation, segment 22 will come into engagement with a contact finger 24 while segment 13 is still in engagement with finger 14. Segment 13 will next leave finger 14, and, after that, segment 22 will leave finger 24. Segment 13 will next engage a finger 17, and segment 22 will afterward engage a finger 23. Segment 13 will then leave finger 17, and, after that, segment 22 will leave finger 23. Segment 13 will then again engage finger 14. The cycle of operation just described will then be successively repeated as long as device M is energized.

Operated in conjunction with switch 3 are a contact 15 which is closed only when switch 3 is in the normal position; a contact 18 which is closed only when switch 3 is in the reverse position; a contact 20 which is closed when switch 3 is either in its normal position or its reverse position; and a contact 21 which is closed only between the normal and the reverse positions of switch 3.

With the apparatus in the condition shown in the drawing, that is, with relay 1TR energized and segment 13 in engagement with contact finger 14, switch magnet 3N will be energized for retaining switch 3 in the normal position in which it is shown, and green lamp G will be lighted for directing traffic movements over switch 3 in its normal position.

When a train enters section A1T, causing de-

55

vice M to be operated, red lamp R will be lighted a brief period before lamp G is extinguished, on account of segment 22 engaging contact finger 24 before segment 13 is disengaged from finger 14. The trainman or motorman is thus warned that the condition of switch 3 is about to be changed. Lamp G will next be extinguished, and lamp R will remain lighted until segment 22 disengages contact finger 24.

10 Magnet 3R will become energized when segment 13 engages finger 17, causing switch 3 to be operated to the reverse position, and switch 3 causing lamp R to again be lighted while switch 3 is in transit. When switch 3 has reached its reverse position, lamp R will be extinguished and lamp Y will become lighted.

As the operation of device M continues, lamp R will again become lighted before lamp Y becomes extinguished, thus warning the trainman that the condition of switch 3 is again about to be changed. Lamp Y will next become extinguished, and lamp R will then again remain lighted until segment 22 disengages contact finger 23.

25 Magnet 3N will next become energized when segment 13 again engages finger 14, causing switch 3 to be returned to its normal position, which causes lamp R to again be lighted while switch 3 is in transit. When switch 3 has reached the normal position, lamp R will be extinguished, and lamp G will again become lighted.

If the car or train approaching signal 1 is to go over switch 3 in its normal position, the trainman will operate his car or train so that it will enter section 1T while lamp G is lighted. If, however, the car or train is to go over switch 3 in its reverse position, the car or train will enter section 1T while lamp Y is lighted.

Having described in general the operation of the apparatus shown in Fig. 1, I shall now describe in detail the operation of the various parts of the apparatus.

I shall assume that a car or train enters section A1T, causing track relay A1TR to become deenergized. A circuit will thereby be completed for operating device M, this circuit passing from a suitable source of current which may be, and which I shall assume is, the same as the source which supplies current to primary windings 5 of 50 transformers a, the circuit therefore passing from terminal BX, through the front point of contact 9 of relay 1TR, contact 10 of relay A1TR, and device M to terminal CX. Device M will therefore start turning its segments 13 and 22 about its axis. As shown in the drawing, before device M is operated, and for a time after its operation begins, magnet 3N of switch 3 is energized by a circuit passing from terminal BX, through the front point of contact 12 of relay 1TR, contact 13-14 55 of device M, and magnet 3N to terminal CX. At the same time, lamp G is lighted by a circuit passing from terminal BX, through the front point of contact 12 of relay 1TR, contact 13-14 of device M, contact 15 of switch 3, contact 16 of relay 1TR, and lamp G to terminal CX.

60 After device M starts to rotate, and before contact 13-14 opens, segment 22 will engage contact finger 24, causing a circuit to be completed for lighting red lamp R, this circuit passing from terminal BX, through contact 22-24 of device M, and lamp R to terminal CX. With lamp R thus lighted contemporaneously with lamp G, the trainman will know that the condition of switch 3 is about to change. After a brief period, contact 70 65 13-14 will open, thereby extinguishing lamp G.

and deenergizing magnet 3N. Lamp R will, however, remain lighted by the circuit previously traced. After a further brief period of time, contact 22-24 will open, causing lamp R to be extinguished.

5 Segment 13 will next engage contact finger 17, causing a circuit to be completed for energizing magnet 3R, this circuit passing from terminal BX, through the front point of contact 12 of relay 1TR, contact 13-17 of device M, and the winding 10 of magnet 3R to terminal CX. With magnet 3R energized, mechanism 3F will operate switch 3 to its reverse position. As soon, however, as switch 3 leaves its normal position, lamp R will again become lighted, by a circuit passing from terminal BX, through contact 21 operated in conjunction with switch 3, and lamp R to terminal CX. Lamp R will continue lighted by this circuit until switch 3 reaches its reverse position, whereupon lamp Y will become lighted by its circuit 15 passing from terminal BX, through the front point of contact 12 of relay 1TR, contact 13-17 of device M, contact 18 of switch 3, contact 19 of relay 1TR, and lamp Y to terminal CX.

If the train is to move over switch 3 in its reverse position, the trainman will move the train into section 1T while lamp Y is lighted, thereby deenergizing device M by opening contact 9 of relay 1TR at its front point. With relay 1TR deenergized, its contact 19 will open the circuit 25 previously traced for lamp Y, causing lamp Y to become extinguished. A third circuit will now be completed for lighting lamp R, passing from terminal BX, through the back point of contact 12 of relay 1TR, and lamp R to terminal CX. A circuit will now also be completed for retaining switch 3 in the reverse position, this circuit passing from terminal BX, through the back point of contact 9 of relay 1TR, contact 20 of switch 3 30 in the reverse position, and magnet 3R to terminal CX. 35

When the train leaves section 1T, the third circuit traced for lamp R will be opened at the back point of contact 12 of relay 1TR, causing lamp R to again become extinguished, and the 45 circuit for lamp Y previously traced will now again become completed at contacts 12 and 19 of relay 1TR, causing lamp Y to again become lighted.

I shall next assume that a second train enters 50 section A1T, causing relay A1TR to again become deenergized. The circuit previously traced for device M will now again be completed through contact 10 of relay A1TR, causing device M to again rotate. Segment 22 will engage contact 55 finger 23 before segment 13 disengages contact finger 17, thereby causing lamp R to become lighted by its circuit passing from terminal BX, through contact 22-23 of device M, and lamp R to terminal CX. Lamp R now being lighted contemporaneously with lamp Y, the trainman will know that the condition of switch 3 is about to be changed. Segment 13 will next leave contact finger 17, causing lamp Y to become extinguished, and segment 22 will then leave contact finger 23, 60 causing lamp R to also be extinguished.

Segment 13 will next engage contact finger 14, causing the circuit for magnet 3N, previously traced, to again be completed. With magnet 3N energized, mechanism 3F will operate switch 3 to 70 its normal position. While switch 3 is in transit between its reverse and its normal positions, lamp R will again be lighted by the circuit previously traced through contact 21 of switch 3. As soon as switch 3 reaches the normal position, lamp G will 75

again become lighted by the circuit previously traced.

If the train is to go over switch 3 reversed, the trainman will wait until lamp Y again becomes lighted before passing signal 1. If, however, the train is to proceed over switch 3 in the normal position, the trainman will now move his train into section 1T while signal 1 is displaying the green indication. As soon as the train enters section 1T, lamp G will be extinguished on account of contacts 12 and 16 of track relay 1TR becoming opened. The circuit previously traced for magnet 3N will also be opened at the front point of contact 12 of relay 1TR. A second circuit for magnet 3N will, however, now be completed, passing from terminal BX, through the backpoint of contact 9 of relay 1TR, contact 20 of switch 3 in the normal position, and magnet 3N terminal CX.

When the train leaves section 1T, the circuits for lamp R and magnet 3N will be opened at the back points of contacts 12 and 9, respectively, of relay 1TR. The circuits first traced for magnet 3N and lamp G of signal 1, through the front point of contact 12 of relay 1TR, will now again become closed, and hence lamp G will be lighted for directing traffic movements over switch 3 in the normal position.

Referring now to Fig. 2, the apparatus is here arranged to provide for lamps Y and G of signal 1 to be alternately lighted due to the alternate closing of contacts 13-14 and 13-17 of device M as in Fig. 1, but the operation of switch 1 will not occur until the train enters section 1T. A second signal 2 is here provided to inform the trainman when switch 3 is in the position corresponding to the indication displayed by signal 1 when his train entered section 1T.

In Fig. 2, a slow release relay 1TPR is energized by a circuit including a front contact of track relay 1TR.

A normal stick relay WNR controlled by contact 13-14 of device M and a reverse stick relay WRR controlled by contact 13-17 of device M are provided for controlling the operation of switch 3 and signal 2.

Manually controllable push button circuit controllers, designated by the reference characters NPB and RPB, are provided for at times energizing relays WNR and WRR, respectively.

Operated in conjunction with switch 3 in Fig. 2 is a contact 37 which, while the switch is in its normal position only, controls a given circuit portion, and which, while the switch is in its reverse position or between the normal and reverse positions, controls a second circuit portion. Also operated in conjunction with switch 3 in Fig. 2 is a second contact 38 which controls a third circuit portion while the switch is in its normal position or between its normal and reverse positions, and which controls a fourth circuit portion when the switch is in its reverse position only.

With the parts of the apparatus of Fig. 2 in the condition in which they are shown in the drawing, lamp G of signal 1 is lighted by a circuit passing from terminal BX, through contact 13-14 of device M, front point of contact 26 of relay 1TR, and lamp G to terminal CX. Relay 1TPR is energized by its circuit passing from terminal BX, through contact 27 of relay 1TR, and the winding of relay 1TPR to terminal CX. Relay WNR is energized by its stick circuit passing from terminal BX, through contact 31 of relay WRR, contact 32 of relay WNR, and the

winding of relay WNR to terminal CX. With relay WNR energized, magnet 3N of switch 3 is energized by its switch circuit passing from terminal BX, through contact 36 of relay WNR, and the winding of magnet 3N to terminal CX. With switch 3 in the normal position and with relay WNR energized, lamp G of signal 2 is lighted by a circuit passing from terminal BX, through contact 37 of switch 3 in the normal position, front point of contact 40 of relay WNR, and lamp G to terminal CX.

I shall assume that, with the parts of the apparatus of Fig. 2 in the condition just described, a train enters section 1T, causing relay 1TR to become deenergized. Device M will therefore be energized by its circuit passing from terminal BX, through contact 9a of relay 1TR, contact 10 of relay 1TR, and device M to terminal CX.

Before contact 13-14 opens, contact 22-24 of device M will close, thus causing lamp R to become lighted by its circuit which is the same as the corresponding circuit previously traced in Fig. 1. Lamp R will therefore be lighted for a brief period of time contemporaneously with lamp G, and hence the trainman will know that the condition of the apparatus is about to change. After a further brief period of time, contact 13-14 will open, causing lamp G to be extinguished. As device M turns still further, contact 22-24 will open, thus extinguishing lamp R.

Segment 13 of device M will next engage contact finger 17, causing a circuit to be completed for lighting lamp Y, passing from terminal BX, through contact 13-17 of device M, front point of contact 25 of relay 1TR, and lamp Y to terminal CX.

I shall further assume that the train is to go over switch 3 in the normal position. The trainman will therefore not pass signal 1 while lamp Y is lighted.

Contact 22-23 will close before contact 13-17 of device M opens, causing lamp R to become lighted by the circuit previously traced in connection with Fig. 1 through contact 22-23. Lamp R is therefore lighted contemporaneously with lamp Y, showing the trainman that the condition of the apparatus is again about to change. After a brief period, contact 13-17 will open, causing lamp Y to become extinguished, and, after a further period of time, contact 22-23 of device M will open, causing lamp R to again become extinguished.

Contact 13-14 of device M will next become closed, completing the circuit previously traced for lamp G. With lamp G now lighted, the trainman will advance his train into section 1T, causing relay 1TR to become deenergized. Relay 1TR, upon becoming deenergized, opens the circuit for lamp G at the front point of its contact 26, causing lamp G to become extinguished, and, through its contact 28, closes a third circuit for lamp R of signal 1, causing this lamp R to again be lighted. The circuit for relay 1TPR is also opened at contact 27 of relay 1TR, but, on account of relay 1TPR being slow releasing, a pick-up circuit will be closed momentarily for energizing relay WNR, this circuit passing from terminal BX, through contact 13-14 of device M, back point of contact 26 of relay 1TR, front point of contact 39 of relay 1TPR, and the winding of relay WNR to terminal CX. Since relay WNR is already energized by its stick circuit previously traced, there will be no change in the condition of relay WNR or of lamp G of signal 2. After a brief period of time, relay 1TPR

will permit its contact 30 to open at its front point, thereby breaking the pick-up circuit previously traced for relay WNR through this contact.

- 5 When the train leaves section 1T, relay 1TR will again become energized, thus again completing the circuit for lamp G of signal 1, causing lamp G to again become lighted. With relay 1TR again energized, relay 1TPR will also again become energized by its circuit previously traced.

I shall next assume that a second train enters section A1T, causing relay A1TR to again become deenergized and device M to again become operated. After a time, lamp Y of signal 1 will again become lighted as previously described.

I shall now further assume that the train is to go over switch 3 in the reverse position. The trainman will therefore move his train into section 1T while lamp Y of signal 1 is lighted, thus 20 causing lamp Y to be extinguished and lamp R of signal 1 to again be lighted. A circuit will now be completed for energizing relay WRR, this circuit passing from terminal BX, through contact 13-17 of device M, back point of contact

25 of relay 1TR, front point of contact 29 of relay 1TPR, and the winding of relay WRR to terminal CX. Relay WRR, upon becoming energized, opens its contact 31 in the stick circuit for relay WNR, causing relay WNR to become deenergized. The stick circuit for relay WRR then becomes closed, passing from terminal BX, through contact 33 of relay WNR, contact 34 of relay WRR, and the winding of relay WRR to terminal CX.

35 With relay WNR deenergized, the circuit previously traced for lamp G of signal 2 is open at the front point of contact 40 of relay WNR, causing lamp G to be extinguished. When relay WNR becomes deenergized, lamp R of signal 2 becomes 40 lighted by a circuit passing from terminal BX, through contact 37 of switch 3 in the normal position, back point of contact 40 of relay WNR, and lamp R of signal 2 to terminal CX.

With relay WNR deenergized, the circuit for 45 magnet 3N of switch 3 is open at contact 36 of relay WNR, and, with relay WRR energized, the circuit for magnet 3R is now closed, passing from terminal BX, through contact 35 of relay WRR, and the winding of magnet 3R to terminal CX.

50 With magnet 3R energized, switch mechanism 3F will move switch 3 to the reverse position. As soon as switch 3 leaves the normal position, a second circuit will be completed for lighting lamp R of signal 2, this circuit passing from terminal BX, through contact 37 of switch 3 in an intermediate position, contact 38 of switch 3 in an intermediate position, and lamp R to terminal CX. The circuit first traced for lamp R of signal 2 is now open at the normal position of contact 37 of switch 3.

55 As soon as switch 3 reaches the reverse position, the second circuit for lamp R will be opened at contact 38 of switch 3, and a circuit will be completed for lighting lamp Y of signal 2, this circuit passing from terminal BX, through contacts 37 and 38 of switch 3 both in the reverse position, front point of contact 39 of relay WRR, and lamp Y of signal 2 to terminal CX. With lamp Y of signal 2 lighted, the trainman will 60 know that switch 3 is in the reverse position, and he will proceed accordingly.

65 When the train leaves section 1T, relay 1TR will again become energized, causing lamp Y of signal 1 to again become lighted by its circuit previously traced. Relay 1TPR will also again

become energized by its circuit previously traced through contact 27 of relay 1TR.

I shall again assume that a train passes signal 1 while lamp Y of signal 1 is lighted, but that the trainman finds that he should go over switch 3 in the normal position instead of in the reverse position. He will therefore depress circuit controller NPB, completing a second pick-up circuit for relay WNR, this circuit passing from terminal BX, through controller NPB, back point of contact 30 of relay 1TPR, and the winding of relay WNR to terminal CX. Relay WNR, upon becoming energized, opens the stick circuit for relay WRR at its contact 33, causing relay WRR to become deenergized. A stick circuit will then 15 be completed for relay WNR as previously traced.

As soon as switch 3 again reaches the normal position, the circuit previously traced through contacts 37 and 38 of switch 3 in the intermediate position for lighting lamp R of signal 2 will 20 be open, and hence lamp R will be extinguished. Lamp G of signal 2 will now again be lighted by the circuit previously traced.

From the foregoing description and the accompanying drawing, it follows that apparatus embodying my invention provides means controlled by an approaching train for operating a switch to the normal and reverse positions, and for selectively retaining a switch in, or operating it to, the normal or the reverse position according as 30 the train passes a given signal while the signal is displaying a first or a second indication, respectively. This system is particularly adapted for use on electric railways having cars which can start and stop quickly, but may also be modified, in a manner which will be obvious to persons skilled in the art, for use with heavier trains.

35 Other schemes have been provided for controlling the position of a switch in accordance with the speed at which a train approaches. An 40 advantage of the present scheme is that the position of the switch does not depend on the speed at which a train approaches. A car or train may even stop on the section in the rear of the signal without causing any difficulty in the operation of the apparatus.

45 Although I have herein shown and described only two forms of railway traffic controlling apparatus embodying my invention, it is understood that various changes and modifications may be 50 made therein within the scope of the appended claims without departing from the spirit and scope of my invention.

Having thus described my invention, what I claim is:

55 1. In combination, a stretch of railway track including a switch, a first and a second contact, means set into operation by a train upon its arrival on said track a given distance from said switch for alternately closing said first and second contacts, means controlled by said first contact in its closed position for operating said switch to a given extreme position, means controlled by said second contact in its closed position for operating said switch to the reverse position, a signal capable of displaying a first or a second indication, means controlled by said first contact and by said switch in said given extreme position for energizing said signal to display its first indication, means controlled by said second contact and by said switch in the reverse position for energizing said signal to display its second indication, and means controllable by said train upon its arrival on said track a second given distance from said switch for discontinuing the 70 75

alternate closing of said contacts while one of said contacts is closed and thereby leaving the means controlled by said one contact in the condition for retaining said switch in the corresponding position.

2. In combination, a stretch of railway track including a switch, a signal capable of displaying a first or a second indication for directing traffic movements over said switch in the normal or the reverse position respectively, a first and a second contact, means responsive to traffic conditions on said track for alternately closing said first and second contacts while said track is occupied within a given distance in the rear of said signal, means responsive to said first contact in its closed position for operating said switch to the normal position and for then operating said signal to display its first indication, means responsive to said second contact in its closed position for operating said switch to the reverse position and for then operating said signal to display its second indication, and means controllable by a train upon passing said signal for discontinuing the alternate closing of said first and second contacts while one of said contacts is closed and thereby leaving said one contact closed, and means responsive to a train on said track upon passing said second signal and for discontinuing the alternate closing of said first and second contacts while one of said contacts is closed and thereby leaving said one contact closed, and means responsive to a train on said track upon passing said second signal and for discontinuing the alternate closing of said first and second contacts while one of said contacts is closed and thereby leaving said one contact closed.

3. In combination, a stretch of railway track including a switch, a signal capable of displaying a first or a second or a third indication, a first and a second contact and also a third and a fourth contact, means responsive to traffic conditions on said track for repeatedly closing and then opening each of said contacts in the order named while said track is occupied within a given distance in the rear of said signal so that the first contact becomes closed and then the second contact becomes closed and next the first contact opens and later the second contact opens and then the third contact closes and later the fourth contact closes and next the third contact opens and then the fourth contact opens and this cycle of operation then begins again, means responsive to said first contact in its closed position for operating said switch to the normal position and for then operating said signal to display said first indication, means responsive to said second contact in its closed position for operating said signal to display said third indication, means responsive to said third contact in its closed position for operating said switch to the reverse position and for then operating said signal to display said second indication, means responsive to said fourth contact in its closed position for operating said signal to display said third indication, and means controllable by a train upon passing said signal for discontinuing the cycle of operation of said contacts while either said first or said third contact is closed for retaining said switch in the corresponding position.

4. In combination, a stretch of railway track including a switch, a signal capable of displaying a first or a second indication for directing traffic movements over said switch in its normal or its reverse position respectively, a second signal in the rear of said first signal capable of displaying corresponding first and second indications for directing traffic movements toward said first signal, a first and a second contact, means responsive to traffic conditions for alternately closing said first and second contacts when a train is within a given distance in the rear of said second signal, means responsive to said first contact in its closed position for energizing said

second signal to display its first indication, means responsive to said second contact in its closed position for energizing said second signal to display its second indication, means controllable by a train upon passing said second signal for discontinuing the alternate closing of said first and second contacts while one of said contacts is closed and thereby leaving said one contact closed, and means responsive to a train on said track upon passing said second signal and for discontinuing the alternate closing of said first and second contacts for operating said switch to its normal or reverse position respectively according as said first or second contact remains closed and for energizing said first signal to display its first or second indication according as said first or said second contact remains closed.

5. In combination, a stretch of railway track including a switch, a signal capable of displaying a first or a second indication for directing traffic movements over said switch in its normal or its reverse position respectively, a second signal in the rear of said first signal capable of displaying corresponding first and second indications for directing traffic movements toward said first signal, a first and a second contact, means responsive to traffic conditions for alternately closing said first and second contacts when a train is within a given distance in the rear of said second signal, means responsive to said second contact in its closed position for energizing said second signal to display its second indication, means controllable by a train upon passing said second signal for discontinuing the alternate closing of said first and second contacts while one of said contacts is closed and thereby leaving said one contact closed, a slow release relay, a circuit for energizing said slow release relay which becomes opened when a train passes said second signal, means controlled by a front contact of said slow release relay and by a train on said track upon passing said second signal for operating said switch to its normal or reverse position according as said first or second contact remains closed, manually controllable means controlled in part by a back contact of said slow release relay for effecting operation of said switch to its normal and reverse positions, and means operated in conjunction with said switch for energizing said first signal to display its first or second indication according as said switch occupies its normal or its reverse position.

6. In combination, a stretch of railway track including a switch, a signal capable of displaying a first or a second indication for directing traffic movements to proceed toward said switch, a first and a second contact, means responsive to a train within a given distance in the rear of said signal for alternately closing said first and second contacts, means controlled by said first contact in its closed position for operating said switch to the normal position and for then energizing said signal to display its first indication, means controlled by said second contact in its closed position for operating said switch to the reverse position and for then energizing said signal to display its second indication, and means controllable by a train upon proceeding further for discontinuing the alternate closing of said first and second contacts while one of said contacts is closed and thereby leaving said one contact closed for returning said switch in the corresponding position.

7. In combination, a stretch of railway track including a switch, a first and a second contact, means controlled by a train approaching said switch for alternately closing said first and second contacts, a signal capable of displaying a first or a second indication, and means controlled by said first contact when closed for operating

said switch to a first extreme position and for then energizing said signal to display its first indication and controlled by said second contact when closed for operating said switch to its other extreme position and for then energizing said signal to display its second indication. 5

HENRY S. YOUNG.
